UNITED STATES PATENT OFFICE.

EDWIN J. KRAETZER, OF SOMERVILLE, MASSACHUSETTS.

BUCKLE.

SPECIFICATION forming part of Letters Patent No. 741,677, dated October 20, 1903.

Application filed January 18, 1902. Serial No. 90,264. (No model.)

To all whom it may concern:

Be it known that I, EDWIN J. KRAETZER, a citizen of the United States, residing at Somerville, in the county of Middlesex and State 5 of Massachusetts, have invented a new and useful Improvement in Buckles, of which the following is a full, clear, and exact description, reference being had to the accompanying drawings, forming a part of this specification, in explaining its nature.

The invention relates to an improvement in buckles. It is applicable to any use which involves the bringing together of individual or separate parts which require to be detachably united.

I will now describe the invention in conjunction with the drawings forming a part of this specification.

Figure 1 is a view in plan of a blank from 20 which the active member of the buckle is made. Fig. 2 is a view in plan of the completed member. Fig. 3 is a view in elevation thereof. Fig. 4 is a view in plan of the same when capped. Fig. 5 represents the two members 25 attached to the counters or parts of an arctic which they are to unite and with the active member in the position it occupies immediately preceding its engagement with the other member. Fig. 6 is a view of the same 30 parts at the beginning of the engagement of the active member with the other member. Fig. 7 is a view of the same parts with the engagement partially completed. Fig. 8 is a 35 view of the same parts, showing them in full engagement. Fig. 9 is a view in plan of said parts fully engaged. Fig. 10 is a view in perspective of an arctic overshoe provided with the buckle, the members of which are represented as engaged.

In the drawings the invention is illustrated 40 as applied to the form of overshoe known as the "arctic," to which it is especially applicable. It embraces two members.

A represents the passive member of my device, which is represented as secured by means 45 of a tongue-loop a to the portion or side A' of the overshoe, the tongue passing through the slot a' in said member and forming a loop by being united to itself or to the shoe side.

The member is represented as having a number 50 of retaining-bars a^2 and of cross openings or slots a^3 between the bars, which slots are

of a size sufficient to permit the entrance and passage of the interlocking shank or tongue of the other member into any one of them 55 that the same may lock in to draw around and against the bar contiguous with such opening. This member when used with the overshoe is outwardly curved in order that it may conform to the shape of the instep of the 60 user, and this rounding formation of the member also tends to the better perfecting of my device, as will hereinafter be shown. B is the other or active member of the buckle, active in the sense that it carries and moves simultaneously with the shank or tongue which engages with the retaining-bars of the passive member aforesaid.

The member B has a head b, represented and as preferably made in the shape of a button-top. At one side of the head is cut the slot b' , affording means whereby it may be united by the strap or loop b^2 to the side or part B' of the overshoe or other thing requiring fastening. It is necessary that the head 70 near its edge be secured by means of a fastening which furnishes a flexible or hinged jointure permitting of the head being turned up or down, and just such a jointure is secured, and economically so, by attaching the 75 head directly to the overshoe by means of the strap or tongue-loop, like as shown. The hinged jointure is also such as permits of the head or top being turned, as from a pivotal axis very near to the passive member, which 80 adaptability is of advantage when it is desired to bring the members into conjunction with one another, as will hereinafter appear. Projecting forward from the front side of the 85 head or button-top near its center as the member is looked at turned up (see Fig. 6) or from the under side of the same as looked at in Fig. 8, where the member is shown turned down, is the tongue b^3 . The tongue b^3 is fixed to the head or top and projects from the same 90 outwardly to curve back beneath the same at the point of its hinged jointure, as before referred to, or at its point of axial turning, and the tongue is of a length to extend beyond said axial point of the head or top and even 95 some little distance beyond the adjacent edge of the same, or so far that the tongue can be made to engage with any one of the cross-bars of the passive member when the head or

top is well turned up and even back, as may be seen in Figs. 5 and 6, and which adaptability of the tongue therein shown is primarily made possible by reason of the fact that 5 the pivotal axis of said head or top is near the passive member, as before explained, when the members are brought into conjunction, wherefore the free end of the tongue may extend beyond the pivotal axis of said head a 10 distance greater than the distance from said pivotal axis to said passive member when said pivotal axis is at its minimum distance from said passive member. However the shank or tongue may be fixed to the head or top to project therefrom, it is material to the further 15 perfection of my device, as will hereinafter appear, that the shank or tongue be so formed that its inner engaging surface, or that surface which contacts or wears against the locking-bar of the passive member when the members 20 are hinged into conjunction, lie along its engaging length substantially the same distance removed from the said pivotal axis of the head or top, even slight changes in the 25 degree of separation being of material consequence as determining whether the members will be brought into conjunction with an increasing or diminishing degree of drawing stress upon the parts to which the members 30 are secured. As illustrating such capability of the conjoining members dependent upon the formation of the shank or tongue I have shown in the drawings the tongue so formed along its inner engaging surface a^4 that while 35 this surface lies along its engaging length substantially the same distance removed from said pivotal axis of the head it is slightly farther removed from said pivotal point, where the tongue projects from the head or top, than 40 at its end, where it extends beyond the edge of the same, while both of these points are slightly farther removed from the said head or top at its point of turning than is the said inner surface b^4 at intermediate point of the 45 tongue's curvature, wherefore the tongue takes the shape substantially as shown, and it is especially to be noted at this point that the position of the head or top at its axial point of turning relatively to the passive 50 member, the feature that the said tongue projects for some little distance beneath and beyond said head at its said point of axial turning, the formation of the tongue and its placement relatively to the head or button-top at its point of axial turning are all points 55 fundamentally important as tending to the perfection of my device, as will hereinafter appear when the mode of its operation and the manner in which the active member combines with the passive member are described. 60

I prefer, though this is in no wise necessary, that the shank or tongue project as integral with the head or button-top. When so made, the shank or tongue will be in part formed 65 from a portion of the head or button-top, the head or top being first formed in the shape of the blank C, (represented in Fig. 1,) which

has the side projection c , and the tongue is cut from this blank and rolled back, leaving the integral jointure, as shown. The opening then left in the head or button-top may be covered, as well as the remainder of the top of the head or button-top, excepting, of course, the attaching-slot, by means of a metallic or other cap or finish applied to the 70 head or button-top in the usual manner of the application of such caps.

The mode of operation of the active member in conjoining with the passive member is as follows: In the first instance the members 80 would have a placement substantially as shown in Fig. 5, the member A would lie passive secured to the part A', while the member B would be turned up in order that it may readily be grasped and held by the thumb 85 and fingers to serve as a draft means for drawing over or straining the parts to which it is secured. Simultaneously with this movement of the head or button-top the end of the tongue or shank projecting forward from the head or 90 button-top, as before described, is brought to engage with any one of the bars a^2 with which it can be drawn over to engage with, and it is especially to be noted at this point that it is by reason of the relative position which the 95 head at its axial point of turning has to the passive member and also on the comparative relative distance the tongue extends beyond said head at its said axial point of turning, whereby its engagement with any one of the 100 bars a^2 of the passive member can be obtained when the head or button-top is in the right-angular or even obtuse-angular position indicated, or, in other words, in a position where it can operate to the best advantage as 105 a lever to still more strain forward the parts to which it is secured by reason of the end of the tongue fulcruming against the bar with which it is in engagement as the head or top is turned forward, as shown in Fig. 6, and it 110 is also to be noted that the arrangement of the parts is such that a considerable degree of leverage strain may be obtained with comparatively little power. Continuing, as the head or button-top is pressed forward the tongue by 115 reason of the strain and its inclined posture begins to draw along the bar against which it is fulcrumed and to lock into the slot alongside it, and it is to be noted, as may be seen in Fig. 7, that with such movement of the 120 shank or tongue there is no giving back of the parts, but the forward strain continued and even increased, a result evident from the fact that the intermediate portions of the tongue, which now fulcrum against the bar, 125 are nearer to the axial point of turning of the head or button-top than the other portions, as before described. From this point as the head or button-top becomes still further pressed forward and down the draft on the 130 parts begins gradually to decrease or diminish until the head or button-top becomes pressed down flat upon the passive member with the tongue locked in by the draft against

the bar of the passive member, as shown in Fig. 8. The easing up of the draft on the parts as the tongue becomes locked into place arises by reason of the fact, as before explained, that this portion of the tongue near or at the point of its projection from the head or button-top is slightly farther removed from the point of its axial turning by reason of the tongue's relative placement and curvature at this point and with the very evident result that there would be a correspondingly giving back of draft on the parts. This easing up on the parts after they have been drawn substantially into place has the especial advantage of preventing a too-close union, which might cause inconvenience. It also acts to advantage in facilitating the starting of unlocking, which of course calls for a reversal of the locking movement of the head or button-top, the said head or button-top being then lifted or picked from its flat position and turned back, thereby moving the shank or tongue upward and backward on the locking-bar until it becomes disengaged from it.

In no way, though, do I desire to limit my invention to where the tongue has the special form of curvature just indicated. Such formation of the tongue has its advantages, as pointed out, and the form is also peculiarly illustrative of the fact, as before referred to, that any slight changes in the tongue's degree of curvature relatively to the axial point where the head or top turns is of material consequence. Still, in so far as the essence of my invention is concerned, the tongue might well be formed so that the part which engages with the bar of the passive member would be at the same relative distance from the head or button-top at its point of axial turning when there would be no slackening or easing up on the parts as they would combine, or the shank or tongue could be so formed by its curvature as to slightly increase the drawing stress upon the parts during the entire operation of their combination, and this without departing from the spirit of my invention, for, as said before, with the shank or tongue placed as it is it is only a question of degree as to what the exact amount of drawing stress shall be. The shank or tongue is also preferably of such a curve and length and the curvature of the passive member is such that when these elements are locked together the tongue will lie close in and against the passive member and its outer end will extend upward to some degree into any slot in the member which may be in advance of the one through which the tongue has been passed, and this serves to reduce the thickness of the buckle and provide a better finish and bearing upon its under surface against the foot of the wearer.

Having thus fully described my invention,

I claim and desire to secure by Letters Patent of the United States—

1. In a buckle, the combination with a passive member, flexibly secured to one of the parts to be joined, and having a slot with a locking edge, of an active member having a head pivotally secured to the other of the parts to be joined, and a shank or tongue fixed to said head, said shank or tongue having its free end projecting beyond the pivotal axis of said head a distance greater than the distance from said pivotal axis to said passive member, when said pivotal axis is at its minimum distance from said passive member.

2. In a buckle, the combination with a passive member, flexibly secured to one of the parts to be joined, and having a slot with a locking edge, of an active member having a head pivotally secured to the other of the parts to be joined, and a shank or tongue fixed to said head, said shank or tongue having its free end projecting beyond the pivotal axis of said head a distance greater than the distance from said pivotal axis to said passive member, when said pivotal axis is at its minimum distance from said passive member, and which shank or tongue is so formed that its inner engaging surface along its entire length lies substantially the same distance removed from said pivotal axis of the head, substantially as and for the purposes set forth.

3. In a buckle, the combination with a passive member flexibly secured to one of the parts to be joined, and having a slot with a locking edge, of an active member having a head or top pivotally secured near one edge to the other of the parts to be joined, and a shank or tongue ^{b3}, fixed to said head to project from about its center, said shank or tongue having its free end projecting beyond the pivotal axis of said head a distance greater than the distance from said pivotal axis to said passive member, when said pivotal axis is at its minimum distance from said passive member.

4. A member of a buckie comprising a head or button-top and a jointless drawing-tongue, a portion of which tongue extends from near the center of the under side of the head or top outward and backward to beyond the edge of the button-top, the said head and tongue being struck from a single blank piece of metal.

5. A blank from which the head or button-top and the drawing-shank of a member of a buckle is made, having a portion which forms the head or top and a part of the shank, and an extension from one edge thereof which forms the remainder of the shank.

EDWIN J. KRAETZER.
